TOILET BOWL EXHAUST INDICATING DISPLAY COVER

Peter Hutton, Englewood, N.J., assignor to American Standard Inc., New York, N.Y., a corporation of Delaware

Filed Apr. 14, 1967, Ser. No. 6,708

Term of patent 14 years

Int. Cl. D20—02; D23—02

U.S. Cl. D80—1

Fig. 6.

Fig. 7.

FIGURE 1 is a top plan view of a toilet bowl exhaust indicating display cover embodying my new design;

FIGURE 2 is a side elevational view thereof;

FIGURE 3 is a cross sectional view taken on line 3—3 of FIGURE 1;

FIGURE 4 is a front elevational view thereof;

FIGURE 5 is a cross sectional view taken on line 5—5 of FIGURE 1;

FIGURE 6 is a bottom plan view thereof; and

FIGURE 7 is a perspective view thereof.

What is claimed is:

The ornamental design for a toilet bowl exhaust indicating display cover, substantially as shown and described.
